UNITED STATES PATENT OFFICE

HARRY J. KETTLEBOROUGH, OF MENDOTA, ILLINOIS, ASSIGNOR TO H. D. CONKEY & COMPANY, OF MENDOTA, ILLINOIS, A CORPORATION OF ILLINOIS

DESIGN FOR A BIRD CAGE

Application filed March 14, 1930. Serial No. 34,862. Term of patent 7 years.

To all whom it may concern:

Be it known that I, HARRY J. KETTLEBOROUGH, a citizen of the United States, and a resident of Mendota, in the county of La Salle and State of Illinois, have invented a new, original, and ornamental Design for Bird Cage, of which the following is a specification, reference being had to the accompanying drawing, forming a part thereof.

The figure is an elevational view of a bird cage showing my new design.

I claim:

The ornamental design for a bird cage, as shown.

HARRY J. KETTLEBOROUGH.
